ELECTRICAL SHIELD

George Irwin MacLaren, Philadelphia, Pa., assignor to Atwater Kent Manufacturing Company, Philadelphia, Pa., a corporation of Pennsylvania

Application April 16, 1934, Serial No. 720,918

2 Claims. (Cl. 250—27.5)

My invention relates to electrical shields for radio apparatus. In apparatus employing thermionic tubes, it is generally necessary or desirable to shield parts of the circuits and thermionic tubes to avoid undesirable reactions between the various elements.

It has previously been the practice to shield thermionic tubes by metallic shields. Such shields may be drawn or fabricated from sheet metal. The shield covers the thermionic tube and fastens to a base fitting. The connection between the base fitting and the shield may be a forced fit or a bayonet lock type. In any event the grounding of the shield depends upon the fit. Too tight a fit, may result in a bent or broken shield; too loose a fit, gives imperfect grounding and rattling of the metal parts from vibration. Such vibration is present in portable sets and sets where the loudspeaker is mounted on or near the base.

I propose to overcome these difficulties by an improved method of shielding which will eliminate the base fitting. My invention will also result in savings of material and labor over the previous types of tube shields.

Figure I shows a sectional view of one form of my shield enclosing a thermionic tube.

Figure II illustrates one method of fabricating the tube shields of my invention.

In Figure I, 1 represents a base member on which is suitably fastened a thermionic tube socket 2. Through a hole 3, the thermionic tube 4 is inserted in the socket 2. Surrounding tube 4 is shield 5. The shield 5 is composed of three laminations. Laminations 6 and 7 are of flexible insulating material; such as, paper stock of about .010 inch thickness. Lamination 8 is a thin metal foil. I have found copper foil of .001 inch thickness suitable, but tin, aluminum or other metal may be used. The inner lamination 8 may be a spiral wrapped paper tube similar to mailing tubes. The laminations 6, and 8 are preferably straight wraps or layers. The reason for this preference is the improved appearance of a straight layer as well as the simplicity of handling the very thin foil layer, which for convenience may be first fastened to the heavier wrapper 6. The various laminations are glued together.

The top of the tube shield may be rolled as illustrated at 9. The roll improves the appearance and may be of sufficient extent to bear against the tube 4 to steady the shield 5. However, the rolled edge 9 is not essential. The straight edge of Figure II may be employed.

In either case, the tube shield may bear on the glass envelope of tube 4 to support and locate the shield.

The metal foil 8 should be grounded to make effective the electrical shielding. A simple terminal may be made by driving a metallic staple 10 through the complete shield 5 and tightly clinching the ends 11 and 12. A wire 13 may be soldered to the staple 10. The length of the wire may be sufficient to permit removal of the shield without disconnecting the end 14 which is usually grounded to the base.

In Figure II, I have shown one method of fabrication in which sections of the laminations have been turned back for illustration purposes. 15 5 represents the complete shield assembly. 7 represents the inner lamination which may be one or more layers of spirally wrapped paper. The metallic foil layer may be seen as 8. The outer layer 6 is shown as a straight wrap with 20 its beginning and end at line 15. The terminal connection already described may be employed or other suitable connections may be substituted.

Although I have shown three laminations, as my preferred construction, it is possible to use 25 two laminations; i. e., one of foil and one of paper. Likewise, although I prefer metallic foil, sprayed metallic coating may be substituted. The outer layer may be suitably painted for best appearance.

The tube shield I have described is just as effective electrically as a solid metal shield. It is cheap to manufacture and will not give a metallic rattle which often results from vibrations in the solid metal shields. Further, the 35 shield of my invention does not require a base fitting. The flexibility of my construction makes it easy to install and eliminates the dangers of bending usually present in the sheet metal type of shield.

I claim:

1. A device for shielding a thermionic tube comprising, a layer of insulating material of cylindrical form having an internal diameter of the order of the maximum external diameter of 45 said thermionic tube, a layer of electrically conductive material attached to the first mentioned layer, an inwardly rolled top edge comprising said layers, and an electrical connection attached to said layers and contacting said conductive layer. 50

2. A device of the character described in claim 1, including a layer of insulating material covering the conductive layer.
